G. F. VAN METER

LOCK FOR WINDOW SASH

Filed Oct. 23, 1922

FIG. 1

FIG. 2

INVENTOR.
BY *George F. Van Meter*
ATTORNEYS.

UNITED STATES PATENT OFFICE.

GEORGE FRANKLIN VAN METER, OF INDIANAPOLIS, INDIANA.

LOCK FOR WINDOW SASH.

Application filed October 23, 1922. Serial No. 596,276.

To all whom it may concern:

Be it known that I, GEORGE FRANKLIN VAN METER, a citizen of the United States, and a resident of Indianapolis, county of Marion, and State of Indiana, have invented a certain new and useful Lock for Window Sash; and I do hereby declare that the following is a full, clear, and exact description thereof, reference being had to the accompanying drawings, in which like numerals refer to like parts.

This invention relates to a window sash lock. The chief object of this invention is to provide a sash lock for windows of the guillotine type, which not only will be economical to manufacture, but will be self-locking and self-centering in its operation.

Another object of the invention is to construct the sash lock in such a manner that when applied to a window the former functions as an anti-rattling device. Furthermore the sash lock when applied to the window prevents, to a considerable degree, swaying of the window in the casing.

The chief feature of the invention in obtaining complete security when it is desired to have windows of the guillotine type open either at the top or at the bottom, or at both the top and the bottom. The lock when attached to the windows secures the same together in the adjusted position and is only releasable from the inside of the window by simply releasing the latch.

The full nature of this invention will be understood from the accompanying drawings and the following description and claim.

In the drawings Fig. 1 is a side elevational view of the inside of the window construction to which the invention has been applied. Fig. 2 is an enlarged side elevational view of the cooperating window parts and the sash lock therefor. Fig. 3 is a sectional view taken on the line 3—3 of Fig. 2 and in the direction of the arrows.

In the drawings 10 indicates a window casing providing the slides 11 for receiving the upper and lower window sashes 12 and 13. In windows of the guillotine type, the upper and lower windows 12 and 13 are slidably supported in parallel planes and are adapted to slide by each other. As shown in Fig. 3 the lower portion of the upper sash frame and the upper portion of the lower sash frame each is beveled and said beveled portions are adapted to en-

gage each other and form a tight joint when the windows are in closed position.

Upon one side portion of the upper window sash 12 there is secured a strap 14, as by means of the screws 15. This strap 14 is provided with a centering recess 16 and a plurality of sockets or recesses 17 which are in line with each other, and which herein are shown as extending entirely through the strap, thereby permitting the strap to be made by a punching process. The length of the strap 14 may be as desired, the same being determined by the number of positions in which it is desired to lock the windows in opened relation.

Associated with the retaining strap 14 is a latch construction and this is shown most clearly in Figs. 2 and 3. In said figures the latch construction is shown as comprising a rectangular housing portion 18, which rectangular housing portion is open upon one face and its opposite face is provided with an aperture 19. The apertured face likewise is provided with an integral projection 20, which projection extends inwardly into the housing and forms a spring retainer. The housing suitably supports within the same, and opposite the aperture 19, a pivot pin 21, and said pivot pin 21 pivotally supports a bell crank lever 22 having an arm portion 23 which extends through the aperture 19 and terminates in a suitable loop 24 adapted to receive a cord or chain 25 carrying a ring 26. The other end of the lever 22 terminates in two transverse wing portions 27 and a projecting locking tooth 28 having a beveled edge 29. Extending from the tooth 28 is a projection 30 which also is beveled, and extending inwardly and oppositely from the beveled tooth 28 is a projection 31 which forms another spring retainer. Interposed between the bevel tooth 28 and the apertured face of the housing 18 and surrounding both projections 20 and 31 is a coil spring 32 which normally presses the bell crank lever outwardly from the housing so that the tooth 28 engages the strap 14 and preferably positions said toothed portion 28 in one of the openings 17. The housing is likewise provided with a flanged base 33 which is suitably apertured to receive securing means 34, herein shown in the form of screws which secures said base, and, therefore, the housing to the upper portion of the lower sash 13 adjacent the strap 14.

From the foregoing it will be noted that the device consists essentially of but the following; a socket forming, strap, an integral housing, a pivot, a spring and a bell crank 5 latch.

The operation of the device is as follows: When the upper sash is raised from an open position, the wall of the apertured socket 17 engages the beveled edge 29 of the tooth 10 28 and tilts the pivoted latch in position to the spring 32, and thus the window may be moved upwardly to close the same. In a similar manner the lower window sash 15 may be moved downwardly and the pivoted latch will again be tilted as the beveled edge 29 engages the successive slot edges. However, when it is desired to move the 20 upper window sash downwardly or the lower window sash upwardly, the flat edge of the tooth 28 engages the first socket 17 and is seated therein by means of the spring 32 and thus further relative movement of the two windows is prevented unless the lever is tilted by suitable means, such as the 25 chain 25 herein shown, whereupon the window may be moved to the desired position and therein latched.

It will be noted that with the foregoing construction it is possible, see Fig. 1, to position the upper and lower window sashes 30 in such relationship that an opening is provided at the top and bottom of the window frame or casing, thereby insuring circulation and also insuring that further opening 35 movement is impossible, except from within the house or from the inside of the window. Any movement of the lower window upwardly will likewise move the upper window upwardly, and any movement of 40 the upper window downwardly will likewise move the lower window downwardly, so that the relative positions of the windows are thus fixed. Should, however, the upper window be moved downwardly from without, or the lower window upwardly from 45 without, the construction is such that the window will be locked in the next lowest position etc. Therefore, any tampering

with the window will serve to decrease the opening of the window.

50

The construction is such that the bell crank lever bears upon the strap 14 and thus rattling of the window is either prevented or materially reduced. Furthermore, the recess 16 serves as a guide to center the upper window with respect to the lower window in the relative movement of the two and this serves to position the strap 14 in line with the tooth 28. The position 55 of the tooth 28 in any one of the sockets 17 serves to prevent swaying of the window within a limited range.

60

Another feature of the invention permits the removal of the usual center sash lock and this provides a clear glass field in the window. Another feature that the latch provides is that the same is self-locking as hereinbefore suggested and thus when the lower window is positioned in its lowermost position and the upper window in its uppermost position, the latch automatically engages in the lowermost opening 17 and automatically locks the two windows together.

70

The invention claimed is:

A sash lock including an enclosing housing having but one open face and an opening in the opposite face, a bell crank lever pivotally supported therein by two opposite faces continuous with the before mentioned face, said lever having one end projecting through the opening and the opposite end adapted to extend beyond the housing through the open face thereof and said lever also having an inclined face and an edge for window locking purposes on the opposite end, spring means positionable upon within the housing and interposed between the housing and the lever normally forcing said lever locking end outwardly, and a spring retaining projection extending 80 inwardly in and integral with said locking lever locking end and oppositely extending from the face and edge thereof.

85

In witness whereof, I have hereunto affixed my signature.

GEORGE FRANKLIN VAN METER.
